CLAIM

The ornamental design for an electronic atomizing device, as shown and described.

DESCRIPTION

FIG. 1 is a perspective view of an electronic atomizing device shown in an assembled configuration of use;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;

FIG. 9 is a perspective view of an electronic atomizing device, with the atomizer component shown removed from the electronic atomizing device for clarity of disclosure;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of an electronic atomizing device, with the power supply device component shown removed from the electronic atomizing device for clarity of disclosure;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof; and,

FIG. 25 is an enlarged view of area 25 circumscribed in FIG. 9.

The broken lines consisting of evenly spaced dash lines in the drawings depict portions of the electronic atomizing device that form no part of the claimed design.

The dot-dash broken lines in the drawings depict the boundaries of the enlarged views and form no part of the claimed design.
